METAL FRAME BUILDING

William J. McDermott, Port Robinson,
Ontario, CanadaApplication May 2, 1933, Serial No. 668,918
In Canada October 12, 1932

6 Claims. (Cl. 189—1)

This invention relates to a metal frame construction for buildings particularly small buildings such as dwelling houses and other similar small building structures.

5 While steel is widely used in the construction of office, factory and other large buildings, there have been only very few dwelling houses or similar small buildings constructed with metal framing members. This is apparently due to the 10 greater cost of construction compared with wood, together with certain mechanical disadvantages.

The present invention provides a metal framing structure for dwelling house and other small building structures that can be produced at small 15 cost; that can be assembled at the place of erection without using special tools; that can be assembled with a minimum of labor through the use of interengaging and interlocking parts between beam members; that has main and supplemental vertical members cooperating with the horizontal members and interengaging connecting parts to distribute load stresses efficiently; that provides means for relieving the interengaging connecting parts of substantial direct load 20 stresses; and that secures a cooperation of the vertical, horizontal and roof forming members for securing quick assembly and erection of the frame structure to provide a substantially strong frame considering the size of beam members and other metals used and which further provides for the use of welding where direct connections must be made at the place of erection.

The invention further provides a structure having connecting parts slidably interlocked to 35 assemble the structure in which the connecting parts provide an efficient attachment for beams but at the same time may be arranged so that they do not carry the full load between the parts so connected. These connecting parts facilitate metal frame construction with the use of welded 40 connections throughout.

In the drawings:

Fig. 1 is a side elevation of a building frame structure for a dwelling house constructed of metal members incorporating the features of this invention, only one end of the house construction being illustrated with portions of the roof framing members shown in dot and dash lines with the connector members omitted in order to eliminate unnecessary duplication of detail, it being understood that the portions of the roof forming members shown in full lines illustrate the complete assembled structure of part of the roof, 55 and that the remaining portions of the roof where

the parts are shown in dot and dash lines will be completed in a similar manner.

Fig. 2 is an end elevation of a portion of a house frame structure constructed according to the present invention.

Fig. 3 shows in perspective the arrangement of the connector members between the ridge pole, one of the roof framing members and a main vertical member, the parts being shown with the connector members carried by the ridge pole and 10 roof framing member in disassembled relation, the framing members being shown in dot and dash lines for convenience in illustration.

Fig. 4 illustrates a vertical and a horizontal beam member in dot and dash lines and the relation of the connector members carried thereby, 15 illustrating the details of construction of the connector members in perspective disassembled relation but aligned ready for assembly.

Fig. 5 illustrates the connector members for 20 connecting a roof framing member with a horizontal member in perspective, the parts being in disassembled but aligned relation.

Fig. 6 is a vertical sectional view taken through the ridge pole and one of the roof framing members substantially on line 6—6 of Fig. 1.

Fig. 7 is a detail cross section taken on line 7—7 of Fig. 1.

Fig. 8 is a cross section taken on line 8—8 of Fig. 1.

Fig. 9 is a cross section taken on line 9—9 of Fig. 2.

Fig. 10 is a cross section taken on line 10—10 of Fig. 7.

The drawings illustrate a dwelling house construction but it is to be understood that the invention will apply equally as well to other types of small building structures of a similar character and that the illustration of a dwelling house is to show one embodiment of the invention.

A suitable foundation is provided for the building in the customary manner and is indicated in the drawings at 1. This foundation may be of any conventional form customarily used for providing foundations for buildings of the character illustrated. In providing the foundation for the metal framing structure of the present invention the positions of each of the column members are laid out on the foundation and the upper edge 45 or face is leveled off so that the support for each column member is in the same horizontal plane. When the foundation is completed in this manner as illustrated in the drawings, which will probably be arranged at the level of the cellar 50 55

or basement portion of the building as illustrated in Figs. 1 and 2, the metal framing members forming the building frame are then placed in position and assembled on the foundation in a manner that will be hereinafter described.

It will be understood that all of the metal framing members forming the building frame constructed in accordance with this invention have been previously manufactured to size and constructed in complete form ready for assembly, so that when the framing members are ready for erection on the foundation 1, it is merely necessary to transport them to the place of erection and assemble them on the foundation. All of the parts forming the metal framing structure of this invention are constructed and welded or otherwise assembled together at the manufacturing plant or shop ready for subsequent assembly at the point of erection. The construction and assembly of the metal framing members in the manner indicated is to facilitate the manufacture of the framing members at a central point where the necessary machinery, tools and equipment are available for the economical fabrication of the various parts that are necessary to constitute the building frame so that they only have to be assembled after being delivered to the place of erection by interengaging the interlocking parts.

The main and supplemental vertical members 2 and 3 are first erected on the foundation 1 in the manner illustrated in Figs. 1 and 2 so that they are positioned in their proper spaced relation. These vertical members 2 and 3 may be suitably secured to the foundation whereupon the further erection of the frame structure proceeds by placing the cellar window framing members in position. These cellar window framing members comprise horizontal channel bars 4 that extend between the main and supplemental vertical members 2 and 3 as shown in Figs. 1 and 2 and have a pair of upright channel members 5 secured in spaced relation thereon, so that members 4 and 5 cooperate to form the bottom and the sides of the cellar window opening.

The channel member 4 has a pair of clips 6 forming connector sections secured adjacent opposite end portions, while complementary connector sections in the form of I-beam sections indicated at 7, are mounted on both the main and supplemental vertical members 2 and 3, so that the clips 6 on channel bar 4 may be interengaged in interlocked relation with connector sections 7 by sliding clips 6 on to connector sections 7 through vertical downward movement. The ends of channel bar 4 engage the upper ends of I-beam sections 7 as clearly shown in Figs. 1 and 2, and seat on the upper ends of these I-beam sections so that the position of channel bar 4 relative to vertical members 2 and 3 is determined by this seating engagement of the ends of channel bar 4 on I-beam sections 7. This will position the upper ends of vertical channel members 5 on bar 4 at the proper height for welding to horizontal member 8.

A plurality of horizontal members 8 are provided to extend entirely around the building frame structure in order to support the first floor of the building. The main and supplemental vertical members 2 and 3 and horizontal members 8 are of tubular construction as illustrated in the drawings, for example, as shown in Figs. 4 and 7, and are each constructed of a pair of channel members having their free edge portions arranged in edge to edge relation. The free edges of these

channel members in this edge to edge relation form a substantially square tubular member and are welded together along the abutting edges of the channels to provide a rigid tubular structure.

All of the vertical and horizontal members are secured together by means of connector sections 6 and 7 similar in form to the connector sections 6 and 7 used for securing the cellar window frames in position but which of course may vary in size according to the size of the beam members being connected together and the load to be carried. The connector sections 6 and 7 that provide for the connection of a horizontal member 8 to a vertical member 2 or 3 will be of substantially heavy construction while the similar connector sections used for securing frame members for windows, doors and the like such as the channel bar 4 forming the cellar window frame, may be secured in place by connector sections that are relatively small.

Each connector section 6 comprises, as illustrated in Fig. 4, a strip of metal formed to provide a pair of right angular extending portions 9 and 10. The portion 9 is applied to the underface of beam member 3 at the proper spaced position inwardly from the end thereof so as to be in surface contact with the surface of beam member 2, to which it is permanently welded. The portion 10 will then extend laterally downward from beam member 8 while the side edges of the portion 10 are provided with integral extensions 11 bent inwardly toward each other and overlying the portion 10 in spaced relation, so as to cooperate with portion 10 to form a socket. The free ends of the lips or inwardly extending portions 11 terminate in spaced relation as illustrated in Figs. 4 and 7.

On all of the vertical members connector sections 7 are provided, consisting of a section of an I-beam. One side portion 12 of the I-beam section is secured in surface contact with the face of the tubular member forming a vertical member. Where the side portion 12 overlies the joint between two of the channel members forming the vertical member, the welding of side portion 12 to the vertical member cooperates in securing these channel members in assembled relation. The web portion 13 of connector section 7 extends laterally from the vertical member and the other side portion 14 of section 7 is supported in spaced parallel relation to portion 12. The clip 6 has portions 10 and 11 so formed that they are in complementary relation to side portion 14 and web 13 of section 7, in order that the portions 11 will engage the inner faces of side portion 14 while portion 10 of clip member 6 will engage the outer face thereof in the manner clearly illustrated in the drawings, for example, in Fig. 7. This provides an interlocking connection between a horizontal beam member 8 and a vertical member 2 or 3, and the end portion of the horizontal beam seats on the upper end of connector section 7, while the clip member prevents lateral separation of horizontal member 8 from the vertical members.

Therefore, it will be seen that the position of each horizontal member 8 in the building frame structure is determined by the position of connector section 7 on the vertical member. In manufacturing the vertical members at the shop it therefore, becomes an easy matter to determine the proper position of each horizontal member 8 in the building structure, because it is only necessary to measure the distance along the vertical member for each of the connector sec-

tions 7, in view of the seating cooperation between the ends of the horizontal members and the upper ends of connector sections 7. In this way a considerable portion of the stress is applied directly from a horizontal member to a vertical member without affecting the interlocking connection between the connector sections 6 and 7.

The manufacture of vertical, horizontal and other framing members can be obtained on a production basis by using welding forms for these members that will accurately position and hold the connector sections in proper position while being welded to the framing members.

15 The horizontal members 8 are constructed so that they extend between main vertical members 2, and have the ends of the horizontal members terminating in substantial engagement with the sides of the main vertical members 2. Intermediate portions of horizontal members 8 engage the ends of supplemental vertical members 3. The horizontal members 8 and supplemental vertical members 3 are secured together by means of connector sections 6 and 7 in the manner shown 20 in Figs. 1 and 2 through the provision of connector sections 7 at the ends of the supplemental vertical members on opposite sides thereto with the provision of connector sections 6 secured to the intermediate portion of horizontal member 8 for interlocking connection with connector sections 7 on supplemental vertical members 3.

With the use of the main and supplemental vertical members assembled with the horizontal members 8 in this manner, in forming the framing structure carrying the first floor of the building, it will be seen that a substantial portion of load on the building at this level is distributed directly in end relation to the supplemental vertical members 3 and by means of the I-beam connector sections 7 direct to the main vertical members 2. In this way a cooperation is obtained between the parts that provides for the ready assembly of the horizontal and vertical members and the efficient cooperation of these members in their connected relation to distribute load stresses.

The horizontal members 8 are assembled in position by vertical downward sliding movement to engage connector sections 6 with connector sections 7, and when all of the vertical members 8 for the first floor are in position, the upper ends of the cellar window framing channels 5 may be welded thereto.

Then the erection of the building proceeds toward the second floor structure through first positioning the window and door framing members generally indicated at 15 and 16 respectively, in assembled position, as shown in Figs. 1 and 2. Each window framing structure 15 comprises a pair of supplemental vertical members 17 in the form of channel bars arranged in opposed relation with their flanges extending outwardly. At the upper and lower ends of the channel bars 17 are provided I-beam connector sections 7 assembled with clip sections 6 on horizontal members 8. The lower ends are first assembled with connector sections 6 on horizontal members 8 forming the first floor supporting structure. This will position the window framing members 15 in position between the main vertical members 2 as shown in Figs. 1 and 2.

Intermediate the ends of channel members 17 are provided connector sections 7 for receiving connector sections 6 carried by horizontal channel bars 18. The opposite ends of channel bars

18 are connected to main vertical members 2 by means of connector sections 6 and 7 carried respectively by the channel members 18 and vertical members 2.

This will assemble the window framing members 15 in position and hold them rigidly assembled between vertical members 2. Each window framing member 15 in addition to including a pair of vertical channel members 17 comprises top and bottom channel bars 19 that are welded at the ends to the channel members 17 in the desired spaced relation to define a window opening of the desired size. The channel members 19 are welded at the shop to members 17 so as to form a rigid window framing structure.

The door framing member 16 comprises a pair of spaced vertical channel members 20 that are mounted in spaced relation the proper distance apart to define the door opening for the building by means of a channel member 21 having the ends welded thereto in position to define the top of the door opening. The lower ends of members 20 carry I-beam connector sections 7 that engage in clips 6 carried by horizontal member 8 as shown in Fig. 1 and properly space the lower ends of channel members 20 to form the door opening. The channel bars 18 are provided with connector sections 6 cooperating with complementary sections 7 on channel members 20 and vertical members 2 so as to cooperate in securing the door framing members 16 in proper position in the building frame.

When these window and door framing members are assembled into the building between vertical members 2 in the manner above described, the structure is then ready to receive horizontal members 8 that are provided to form the second floor support. They are placed in position by vertical downward movement to engage the complementary connector sections into interlocked relation in the manner hereinbefore described, the assembled relation of horizontal members 8 for the second floor of the building being clearly illustrated in Figs. 1 and 2 of the drawings. It will be understood that connector sections 6 are applied to the under face of the second floor horizontal members 8 in proper position to interengage in interlocked relation with the connector sections 7 carried by supplemental vertical channel members 17 and 20 forming the window and door framing members. The ends of the second floor horizontal members 8 are also secured to vertical members 2 by means of complementary connector sections 6 and 7 carried by the respective members as above described.

If the building contains any additional stories above the second floor before the roof is put in place, it will be understood that the framing members for the windows, doors and other parts carried by and above the second floor are made and arranged in position in the manner described for these framing members for the first floor structure.

They are all assembled in relation by interengaging the connector sections together, so that in each case, the members that extend in horizontal relation will have portions of the under faces either intermediate the ends, or at the ends, seated at the upper ends of supplemental vertical members, or on the upper ends of connector sections 7 carried by main vertical members. The next part of the construction is the erection of the roof forming members and the parts associated therewith.

At the ends of the building as shown in Fig. 2

the central vertical member 2 extends from the foundation to the ridge of the roof and at the upper end is cut to provide a pair of angular portions 22 seating the ends of the end roof rafters 23 that extend in angular relation in the usual manner to form the support for the roof of the building. Connector sections 24 as shown in Fig. 3 formed of I-beam sections similar to sections 7 are provided on opposite sides of central vertical member 2 at opposite ends of the building adjacent the upper end of vertical member 2.

The upper ends of sections 24 are beveled or inclined as shown in Fig. 3 to provide a further seat for the under surface of roof rafters 23.

Complementary connector sections 25 constructed in exactly the same manner as sections 6 are provided on the under sides of rafters 23 adjacent the upper ends, the difference between sections 25 and sections 6 being that in the sections 25 the angular portions 26 and 27 are arranged in acute angular relation instead of in right angular relation as in sections 6, the portion 26 in each case being welded to the under face of the rafter 23.

The rafters 23 are of tubular metal construction formed of channel members welded together at abutting edges in the same manner as vertical member 2 and horizontal members 8. The rafters 23 are assembled by vertical downward movement to interlock sections 25 with connector sections 24. At the same time connector sections 28 are interlocked in a corresponding manner with connector sections 29, these sections 28 and 29 being positioned at the lower ends of roofing rafters 23, the sections 28 being welded to the roofing rafters and sections 29 welded to horizontal members 8 except that, at the ends of the building, where sections 29 are welded to the upper ends of the vertical members 2 arranged at the corners of the building.

Connector sections 28 are constructed in the same manner as sections 6 and 25 except that the portions 30 and 31 are arranged in obtuse angular relation as shown in Fig. 5, the portion 30 being welded to the under side of rafter 23 near the lower end thereof as illustrated in Fig. 2. The connector sections 29 are formed of I-beam sections that have the upper edges thereof beveled or inclined as indicated at 32 in Fig. 5 so that the under face of the lower end of rafters 23 seat on inclined faces 32 of sections 29.

After rafters 23 at the ends of the building are assembled in position as illustrated in the drawings, the ridge pole or beam 33 is then assembled into position. This ridge pole is of tubular cross section constructed from a pair of channel members welded at the edges in the same manner as horizontal members 8 and vertical members 2, ridge pole 33 being arranged so that two adjacent sides thereof are in angular relation to the vertical and in substantially perpendicular relation to roof rafters 23.

Connector sections 34 are welded to each end portion of ridge pole 33 and are constructed as shown in Fig. 3, being similar to connector sections 6 except that angular portion 35 extending substantially at right angles from portion 36 is formed with angularly arranged portions 37 and 38 to have surface contact with a pair of adjacent faces on the underside of ridge pole 33 to which portions 37 and 38 are rigidly welded. The connector sections 34 on the ends of ridge pole 33 are slidably interlocked by vertical downward movement with complementary connector sections 39 on the inner faces of main vertical members 2 as

shown in Fig. 3 in detail. The connector sections 39 are welded to main vertical members 2 and are formed of I-beam sections similar to sections 7, and mounted in a similar manner on vertical members 2. The sections 39 differ in structure from section 7 in that side portions 40 secured to vertical members 2 are formed at the upper end with extensions 41 having angular faces to receive the two adjacent under sides of ridge pole 33 at the ends of the ridge pole, so as to form a seat for the ends of the ridge pole to engage and seat on the upper ends of connector sections 39. The manner in which this cooperation between the parts is obtained will be clearly apparent from Fig. 3.

Intermediate the ends of the building, the ridge pole will have the under adjacent faces on either side provided at intervals with connector sections 7 welded thereto while connector sections 29 will be welded on to horizontal members 8 at the sides of the building in corresponding position. These connector sections 7 and 29 intermediate the ends of the building will receive the intervening complementary connector sections 6 and 28 carried at the respective ends of the intermediate roof rafters 23' as illustrated in Figs. 1 and 5. Obviously, a certain amount of clearance is necessary between the complementary connector sections to provide for their convenient assembly. This is found sufficient to provide for the slight lateral movement necessary in the connector section 28 to provide for the subsequent interengaging of connector section 6 on the opposite end of a rafter 23 with a section 7 on the ridge pole. The roof rafters 23' are constructed in exactly the same manner as roof rafters 23, with the exception that at the upper ends roof rafters 23 have the ends beveled for engagement in end to end relation on top of vertical members 2 as shown in Fig. 2, while roof rafters 23' have the ends provided with squared end portions to engage in perpendicular relation against one surface of roof rafters 23 as shown in Fig. 6. This squared end of roof rafters 23' will be recessed at 42 to receive I-beam connector sections 7 on the roof rafter so that connector section 6 on roof rafter 23' may have portion 9 thereof welded to the inner face of the uppermost portion as shown in Fig. 6. This will assemble rafters 23' so that the upper faces thereof will be coincident with one of the upper faces of ridge pole 33 as shown in Fig. 6. This provides a smooth roof surface on which the roof for the building is mounted.

After all of roof rafters 23 and 23' are mounted in position by interlocking the connector sections thereof in a manner that will now be clearly understood, the rafters may be connected by supplemental roof framing members formed of channel bars 43 that extend between adjacent roof rafters 23 and 23'. This is clearly shown in Fig. 1, illustrating these channel roof framing members 43 as being secured to roof rafters 23 and 23' by means of connector sections 6 and 7 respectively. The connector sections 7 are mounted on the sides of roof rafters 23 and 23' and connector sections 6 are welded to channel bars 43, the arrangement of these connector sections being clearly illustrated in Fig. 1 and the manner in which they are constructed and assembled being clearly apparent from the previous description of the structure of these sections. Each channel bar 43 is assembled in position by downward movement in the plane of the roof rafters to engage connector sections 6 with connector sec-

tions 7 with the ends of channel members 43 seating on the ends of connector sections 7.

Where windows are to be arranged at the ends of the building above the second floor level in a 5 building of the character illustrated in the drawings, so that the windows come in the attic or roof portion of the building, these windows may be formed by providing a vertical channel bar 45 forming one side of the window while the other 10 side may be formed by vertical member 2 as shown in Fig. 2 with horizontal channel members 46 and 47 secured in assembled relation by means of connector sections 6 and 7 as shown in Fig. 2.

The connector sections 7 will be secured in each 15 case by welding or the like on vertical member 2 and vertical channel member 45, while the complementary connector sections will be carried by the horizontally extending members 46 and 47. Vertical channel member 45 will be secured by 20 connector sections 6 and 7 to the upper face of horizontal member 8. The horizontal channel bars 46 in being secured by connector sections 6 and 7 to vertical member 2 may also extend at the opposite end to roof rafter 23 and be secured 25 thereto by means of a pair of connector sections similar to that disclosed in Fig. 5 in which a connector section 28 will be applied to the channel member 46 and a connector section of I-beam cross section similar to connector section 7 will 30 be applied to the under face of roof rafter 23. Horizontal channel bars 46 may be readily assembled in the building as shown in Fig. 2, by first attaching bar 46 to rafter 23 before it is placed in position in the building. Rafter 23 and bar 46 35 can then be placed in position in the building as shown in Fig. 2 by dropping the same into position by vertical downward movement to interengage the complementary connector sections on the rafter 23 and bar 46 with the connector sections 40 on adjacent parts of the building with which they are intended to interlock, as shown in Fig. 2. A supplemental vertical channel bar 48 may also be used to cooperate with the end structure of 45 the building frame where members 45 and 46 are provided for forming a window in the roof portion of the building, in which the vertical member 48 will be connected by connector sections 6 and 7 to the horizontal channel bar 46 and to horizontal member 8 on the second floor level of 50 the building as shown in Fig. 2. This member 48 will cooperate with members 45 and 46 to provide a reinforcement for the roof structure and distribute part of the load stress on roof rafter 23 to vertical members 2 and 8 and to the supplemental vertical members 3 and 17.

Where a ceiling is to be constructed in the 55 attic of the building, suitable ceiling supporting channel bars 49 may be provided extending horizontally across the building and having the ends seated in the channel in the supplemental roof forming channel members 43 as illustrated in Fig. 2. It will also be understood that should the building have a ridge pole of such length that some intermediate support between the ends of 60 the building is necessary for the ridge pole, this may be provided by vertical members 2 extending through the central portion of the building and secured to the ridge pole by means of suitable connector sections such as those shown in Fig. 3. 65 The central portion of the building may also be provided with other vertical members 2 arranged at intervals to provide for the erection of partitions in order to divide the frame structure for the dwelling house into the various rooms and the 70 vertical and horizontal members for forming the 75

support for floors and forming door frames and the like will be constructed and assembled in exactly the same manner as shown for the outside framing of the building as hereinabove described.

When all of these framing members are assembled into the frame forming structure as illustrated by the drawings, it will be seen that the assembly of the parts does not require any special tools, that the ends of the horizontal members are supported on the connector sections carried by the vertical members, and that the supplemental vertical members have end to end engagement between the horizontal members particularly horizontal members 8 so that they will cooperate with the main vertical members to 15 provide for an efficient distribution of load stresses throughout the building to relieve the connector sections from carrying the entire load; and through the distribution of load in the connector sections in such a way that they are not 20 applied directly to the connecting portions that interlock the connector sections together, but are applied from the horizontal members to the connector section carried by the vertical member and immediately to the vertical member. This 25 provides for an efficient distribution of load stress in the building and for the efficient connection of the members by detachable interlocking connections that may be quickly assembled. This also provides for the construction 30 of all of the framing members of the entire building in the shop, in such a manner, that when they are delivered to the point of erection they may be assembled with a minimum of labor, and in a short space of time, without the use of 35 special structural tools or the fabrication of the parts that enter into the building structure.

The horizontal member 8 in each case carries the floor beams 50 arranged in proper spaced relation to receive and carry the floors of the 40 building.

Buildings may be constructed in accordance with the present invention without the use of special structural beams, because the structural members for the building are formed essentially 45 of channel members that are welded together to form the tubular beams for the vertical and horizontal members. Plain channel sections are used to form other portions of the building as hereinabove described, while ordinary I-beam 50 sections are used without special fabrication to form the connector sections, so that it is only necessary to use standard material cut to length and welded together without special fabrication for the purpose of forming the framing members 55 of a building constructed in accordance with the invention. The connector sections similar to the connector sections 6 are the only ones requiring special formation of the parts and these are of simple form readily manufactured. 60

It will be seen therefore, that a framing structure of metal for small buildings such as dwelling houses and the like is provided by this invention which may be constructed in the shop by the manufacturer without the special fabrication of 65 parts in which buildings of all sizes and dimensions and designs may be made by cutting the parts to proper length and welding the necessary connector sections together to the vertical and horizontal members used in the building, and 70 that they may be assembled by slidble interlocking of the connector sections together at the point of erection, without the use of bolts, nuts, rivets or any other special securing devices, and therefore, without the use of special tools and 75

operations or labor to secure the erection of the building frame.

What is claimed is:

5. In a metal building structure, a vertical member, a horizontal member, and connectors for said members comprising an I-beam section mounted on a side of said vertical member in vertically extending relation with one side secured to said vertical member, and a clip mounted 10 on the under side of the horizontal member formed of a strip having opposite end portions extending in angular relation, one end portion being engaged on and secured to said horizontal member, and inwardly extending flanges on the 15 side edges of the other end portion forming a channel receiving the other side of said section with said flanges and end portion embracing said other side of said section in slidable interlocked relation, said horizontal member having the end 20 thereof seated on the upper end of said section and terminating in adjacent relation to said vertical member.
2. In a metal building structure, a plurality of spaced main vertical members extending the 25 height of the building, spaced horizontal members extending in spaced relation at floor levels between said vertical members, connector sections on said vertical members formed of I-beam sections each having one side secured to said 30 vertical members, the ends of said horizontal members seating on the upper ends of said connector sections, and complementary connector sections on said horizontal members slidably interlocked with the connector sections on said 35 vertical members for securing said horizontal and vertical members in assembled relation, the first-mentioned connector sections cooperating to directly distribute the load stresses of the horizontal members to the vertical members.
3. In a metal building structure, a plurality of spaced main vertical members each formed 40 of a pair of channel members permanently secured together at their engaged edge portions, I-beam connector sections on said vertical members, horizontal members supported on the upper ends thereof, complementary connector sections on said horizontal members, each having angular portions, one secured to said horizontal member, and the other extending laterally in slidable 45 engagement with the free sides of said I-beam connector sections, and extensions on the sides of the last-named portions slidably embracing and interlocking with said I-beam sections.
4. In a metal building structure, a ridge pole 50 of tubular rectangular cross section, a vertical member for supporting said ridge pole, a connector section on said vertical member formed with an angular seat portion for receiving a pair of adjacent faces on the end portion of said 55 ridge pole and a connector section on said ridge pole slidably interlocked with the first-mentioned connector section through vertical downward movement.
5. In a metal building structure, a plurality 60 of spaced parallel main vertical members of a length greater than the distance between two floors of the building, horizontal members extending between said vertical members at floor levels with the ends abutting side portions of said main vertical members, a connector section at each end on the underside of each horizontal member each interengaged in interlocked relation with complementary connector sections on the sides of said adjacent main vertical members, 10 said complementary connector sections being located under the ends of said horizontal members and having said horizontal members seated thereon, said connector sections being formed for slidable interlocking with one another by vertical 15 movement and cooperating to retain said horizontal and vertical members against lateral movement, supplemental vertical members arranged in spaced parallel relation between said main vertical members and having the ends engaging central portions of said horizontal members, connector sections at the upper and lower ends of said supplemental vertical members on the sides thereof slidably interlocked only by vertical movement with complementary connector sections on lower and upper sides respectively of intermediate portions of said horizontal members above and below the ends of said supplemental vertical members, said last-mentioned connector sections retaining said supplemental 20 vertical members in connected position with and between said horizontal members against lateral movement.
6. In a metal building structure, a plurality 25 of main vertical members in spaced parallel relation, horizontal members extending between said vertical members at spaced intervals, complementary connector sections on the side portions of each of said members adjacent the junction between said members interengaged by vertical sliding movement and retaining said members in rigid assembled relation, the end portions of each horizontal member having seating engagement on the connector sections carried by said vertical members in said assembled relation 30 for support thereby, supplemental vertical members intermediate said main vertical members in spaced parallel relation, said supplemental vertical members extending between and having the ends engaging intermediate lower and upper side 35 portions, respectively, of horizontal members above and below said supplemental vertical members, and connector sections on the sides of said supplemental vertical members at the upper and lower ends interlocked only by vertical sliding 40 movement with complementary connector sections on the lower and upper sides respectively of the horizontal members above and below said supplemental vertical members, all of said connector sections cooperating in engaged relation 45 to connect the respective members and retain them against lateral movement.

WILLIAM J. McDERMOTT.
